PURIFICATION OF TOLUIC ACIDS

Chester M. Himel, Menlo Park, Calif., assignor to Richfield Oil Corporation, Los Angeles, Calif., a corporation of Delaware

No Drawing. Application July 1, 1952,
Serial No. 296,716

3 Claims. (Cl. 260—525)

My invention relates to the production of toluic acids in a purified form. More specifically, my invention is concerned with the separation of close-boiling neutral materials from toluic acids produced by the air oxidation of xylenes.

Toluic acids can be prepared by the oxidation of xylenes with air or other oxygen-rich gas. One commercial source of xylenes is to be found in cracked or reformed petroleum oils. Thus, petroleum naphtha which is rich in dimethyl cyclohexanes is dehydrogenated in the presence of hydrogen in accordance with the hydroforming or platforming processes to yield xylenes and other compounds, depending upon the purity of the naphtha fraction processed with respect to content of dimethyl cyclohexanes. The toluic acids produced are associated with neutral impurities which have boiling points close to those of toluic acids and which are therefore difficult to separate from the toluic acids.

My application Serial No. 126,240, now abandoned, and that of Lawrence M. Richards, Serial No. 126,237, now abandoned, both filed November 8, 1949, relate to the production of phthalic acids by the mild oxidation of xylenes to produce toluic acids and a further, more vigorous oxidation of toluic acids to produce phthalic acids, utilizing petroleum xylene fractions as starting materials. In these applications, a petroleum xylene fraction is first subjected to direct, liquid phase oxidation with air in the presence of a catalyst which is soluble in the reaction mixture, such as a cobalt, manganese or cerium soap, particularly the toluate soap. Reaction temperatures of from about 130° C. to about 190° C. are useful. The air oxidation is carried to partial completion, that is, from about 5 percent to about 30 percent by weight of oxygen is absorbed, based on the aromatic content of the petroleum xylene fraction. Such mild partial oxidation, while yielding a lower conversion of the petroleum xylene fraction, favors the production of toluic acids from the xylenes and acetophenone from any ethyl benzene present.

Acetophenone and partial oxidation products such as tolualdehydes are conveniently separated by fractional distillation. When such a distillation is made, there is produced a small fraction of neutral oxidation products which distills between the distillation range of tolualdehydes and the distillation range of the toluic acids. The fraction containing the toluic acids is the last fraction taken off overhead. This fraction, however, also contains varying amounts of neutral materials, depending upon the reaction conditions used in the air oxidation and the handling conditions during the preliminary distillation stages. These neutral materials or neutral oils present in the toluic acid fraction are possibly condensation products of acetophenone and tolualdehydes as well as other oxidation by-products and, as has been stated, have a boiling range close to, or within, the boiling range of the toluic acid isomers. The toluic acid fraction produced from the distillation has a light yellow-green color and a characteristic odor. Analyses indicate

2

that it contains from about 90 to about 98 percent of toluic acids and traces of benzoic acid, with the remainder being the neutral oils mentioned above.

In accordance with my invention, I have found that the materials which contaminate the distilled toluic acids are also responsible for the discoloration and the odor of the acids. Moreover, I have found that such contaminants are quite soluble in saturated hydrocarbons having from 3 to 8 carbon atoms per molecule, and that toluic acids are soluble in such hydrocarbons to only a limited extent. I therefore utilize such hydrocarbons to purify the toluic acids produced by the air oxidation of the petroleum xylene fractions by simply washing the crude distillate composed of the crystalline toluic acids and associated materials with one or more hydrocarbons falling within the class stated above.

This can be done in various ways. For example, the neutral impurities can be solvent extracted by intimately contacting the crude, crystalline toluic acid fraction with propane, butane, pentane, isopentane, hexanes, heptanes, cyclohexane, methyl cyclopentane, dimethyl cyclopentanes, methyl cyclohexane, dimethyl cyclohexanes, or a mixture of these compounds. On the other hand, a process of combined solvent extraction and crystallization can be carried out by charging the molten toluic acid fraction directly from the distillation apparatus or from a toluic acids melt tank into a well-agitated excess of one or more of the solvents just mentioned. After filtration of the crystalline, purified toluic acids, the solvent containing dissolved impurities can be recovered for further use by distillation, in accordance with well known procedures, leaving the impurities as a kettle residue in the solvent recovery still. Preferably I use hydrocarbons having from 4 to 6 carbon atoms because of the better recoveries of toluic acids and the ease of recovery of the solvent. The hydrocarbons which I use are preferably essentially saturated, but they may be in admixture with small amounts of monoolefins of the same range of carbon content.

The following examples illustrated in detail the practice of my invention, and are to be considered not limitative thereof.

Example 1

A commercial xylene fraction having the following analysis:

	Percent
Ortho-xylene	24.5
Meta-xylene	47.0
Para-xylene	17.5
Ethylbenzene	11.0

was used (1500 grams) to charge a stirred autoclave, along with 45 grams of cobaltous toluate catalyst. The reactor was stirred and pressured to 500 p. s. i. g. with air and heated to 150° C. When reaction temperature was reached, 40 cu. ft. of air (measured at room temperature and pressure) was passed into the reactor over a 39-minute period. Effluent gases were released through a back pressure regulator which maintained the pressure in the autoclave at 500 p. s. i. g. The effluent, which weighed 1700 grams, was processed to remove the catalyst and water.

The xylene solution was then divided into a 300-gram aliquot which was distilled to give 196 grams of xylene, 36 grams B. P. 70-130° C./5 mm. and 65 grams of toluic acid fraction B. P. 130-5° C./5 mm. The toluic acid fraction was a light yellow color and had a neutral equivalent of 146, indicating the presence of 7 percent neutral impurities. The yellow solid was ground and extracted once with 100 cc. of petroleum ether (B. 35-60° C.) to give a pure white residue which had a neutral equivalent of 140. A second extraction gave 55 grams of

white crystals having a neutral equivalent of 136, corresponding to pure toluic acids.

Example II

An oxidation effluent similar to that in Example I was processed to give 100 grams of distilled toluic acid fraction (sample A) and 100 grams of non-distilled toluic acids from which the lower-boiling neutral fractions were removed. This material was designated as sample B. Two different samples of commercial toluic acids produced by the air oxidation of petroleum xylenes in the liquid phase were designated as samples C and D, respectively. These products were ground and extracted with 100 cc. portions of low-boiling petroleum ether (B. 35-60° C.) with the following results:

Sample	Start			1st Extraction			2nd Extraction		
	gms.	N. E.	color	gms.	N. E.	color	gms.	N. E.	color
A	100	144	yellow	80	137	white	76	136	white
B	100	144	brown	85	140	tan	75	138	beige
C	100	140	lt. brown	83	137	white	74	136	white
D	100	136.5	lt. yellow	88	136	white			

After a third extraction of sample B, there remained 70 grams of acids which had a neutral equivalent of 136 and which were beige in color. Also, a 358-gram sample of A was then extracted with 358 ml. of pentane to give 295 grams of white crystals with a neutral equivalent of 136.5.

Example III

A distilled sample of toluic acid having a neutral equivalent of 140 was melted and poured into pentane (4.4 lbs. of toluic acids into 2 liters of pentane) with stirring. Some of the pentane boiled off from the heat of the molten acids and from the heat of crystallization. This pentane was replaced. The toluic acids crystallized in fine white crystals which were filtered and washed once on the filter with additional small quantities of pentane. The product had a neutral equivalent of 136.5 and weighed 4 pounds.

Example IV

A toluic acid product from a low xylene content charge stock was subjected to a preliminary distillation and gave 11 pounds of toluic acid fraction contaminated with aliphatic acids as well as the usual neutral oils. The product was melted and poured into 9 liters of pentane with stirring. The first crystalline fraction removed amounted to 3.5 pounds and had the following analysis:

Neutral equivalent	136.5
Benzoic acid	percent 2.0
Ortho-toluic acid	do 5.0
Meta-toluic acid	do 55-56
Para-toluic acid	do 37-38

Upon further cooling of the mixture, a second crystalline fraction was recovered and amounted to 6.0 pounds having the following analysis:

Neutral equivalent	136.5
Benzoic acid	percent 3.0
Ortho-toluic acid	do 13.0
Meta-toluic acid	do 59-60
Para-toluic acid	do 24-25

The pentane treatment not only effectively removed contaminating materials from this product but also allowed separation into two fractions having different para-toluic acid content. This is of value in the preparation of a feed stock for the production of pure para-toluic acid.

While the foregoing is illustrative of the practice of this invention, the actual washing or extraction step is susceptible to obvious variations. Thus, the relative amounts of crude toluic acids and solvent medium used is not critical, but rather can be varied widely. In actual practice, the relative amounts of crude toluic acids and solvent medium used will depend upon the extent to which the toluic acids are contaminated, upon the particular solvent used, and upon other factors. Further-

more, although the extraction was carried out at room temperature in the examples, it is not absolutely necessary that that be the case, temperatures both above and below room temperature being operable. It is preferred, however, that the extraction be carried out at a temperature not in excess of about 50° C., in order that excessive amounts of the acid will not be dissolved in the solvent, and, for the same reason and also in order to minimize solvent and solvent handling costs, the amount of solvent used should not be too large. These considerations will be readily understood by those skilled in the art.

I claim:

1. In a method for the purification of toluic acids prepared by the liquid phase air oxidation of xylenes, the steps comprising subjecting the reaction product to a distillation operation to remove xylenes and obtain toluic acids admixed with neutral materials having a boiling range close to that of the acids, crystallizing toluic acids, and washing the crystallized acids with a saturated liquid hydrocarbon having from 3 to 8 carbon atoms per molecule at a temperature not in excess of about 50° C.
- 45 2. A method as in claim 1 in which the hydrocarbon is pentane.
- 40 3. A method as in claim 1 in which the hydrocarbon is petroleum ether.
